(57) **CLAIM**

The ornamental design of a humidifier water softener as shown and described.

DESCRIPTION

FIG. 1 is a top, front, side perspective view of a humidifier water softener showing my new design;

FIG. 2 is a bottom, rear, side perspective view thereof;

FIG. 3 is a front view thereof, the opposite rear view thereof being identical;

FIG. 4 is a top view thereof, the opposite bottom view thereof being identical; and,

FIG. 5 is a side view thereof, the opposite side view thereof being identical.

The broken lines depict portions of the humidifier water softener that form no part of the claimed design.
